UNITED STATES PATENT OFFICE.

JOHN ERICKSON, OF CHICAGO, ILLINOIS, ASSIGNEE, BY MESNE ASSIGNMENTS, TO
FIRST TRUST AND SAVINGS BANK, TRUSTEE, OF CHICAGO, ILLINOIS.

TELEPHONE APPARATUS.

1,131,624.

Specification of Letters Patent.

Patented Mar. 9, 1915.

Application filed November 12, 1908. Serial No. 343,044.

To all whom it may concern:

Be it known that I, JOHN ERICKSON, a citizen of the United States of America, and resident of Chicago, Cook county, Illinois, have invented a certain new and useful Improvement in Telephone Apparatus, of which the following is a specification.

My invention relates to automatic telephone exchange systems, and more particularly to the devices by which the subscribers release the switches at the exchange or central station.

An object of my invention is to provide improved means for insuring a release of the said automatic switches, even though the subscriber's hook-switch, by means of which the releasing is accomplished, be given a quick downward movement.

Another object is to provide certain novel features and details of construction and combinations tending to increase the general efficiency of a telephone exchange system of this particular character.

To the foregoing and other useful ends, my invention consists in matters hereinafter disclosed and claimed.

In the accompanying drawings, Figure 1 shows my improved switch-hook device in normal position—that is, when the receiver is in place on the switch-hook; the dotted lines show the position the hook takes when the receiver is removed from the switch-hook. Fig. 2 is a cross-section of the device taken on the line 2—2 in Fig. 1. Fig. 3 is a cross-section on the line 3—3 in Fig. 1, showing the method of securing the switch-hook to the supporting frame. Figs. 4 and 5 are detail views of different parts. Fig. 6 is a cross-section taken on line 6—6 in Fig. 5. Fig. 7 shows the bifurcated end of the switch-hook. Fig. 8 shows my switch-hook with circuit connections for its use in connection with an automatic telephone system.

The calling device A of the substation in connection with which my switch-hook device is shown controls the circuit of a battery B for operating the connector C of the central office. The switch-hook device, as shown in Fig. 1, comprises a base or frame 2 upon which the various parts are suitably mounted. At the lower part of the said frame are formed the brackets 3, and at the upper part are formed the brackets 4 and 5. The bracket 4 is provided as a stop or rest for the switch-hook 6 when the receiver is

removed, as shown by the dotted lines in Fig. 1. Upon the bracket 5 is mounted the hook-operating spring 7, by means of the screw 8. Furthermore, the bracket 5 serves as a stop or rest for the switch-hook 6 when the receiver is restored and the said switch-hook is down. Therefore, the brackets 4 and 5 limit the movement of the said hook 6. By means of the screw 9 the hook is suitably secured to the frame 2. About this screw the switch-hook is adapted to move when the receiver is restored and removed. When the receiver is restored to the switch-hook the weight of the said receiver is sufficient to carry the switch-hook to its lowermost position, against the tension of the spring 7, which position is reached when the end 10 strikes the stop or rest 5. Now when the receiver is removed the switch-hook 6 reaches its uppermost position, and the end 10 strikes the stop 4. The switch-hook arm 11 with the bushing 12 is adapted to control a group of springs D. Near the extremity 10 of the switch-hook 6 the dog 14 is suitably secured by means of the screw 13. The said dog 14 is normally maintained in engagement with the pin 15 by the retracting spring 16, one extremity of which is secured to the dog 14 by means of the pin 17, and the other end is secured to the switch-hook 6 by means of the pin 18. Furthermore, to the switch-hook 6 is suitably secured the locking spring 19, the function of which will be explained.

Rotatably secured to the frame 2 by means of the screw 20 is the wheel or disk 21 which controls the group of release springs E by means of the bushing 22. This bushing is mounted upon the pin 23 (Fig. 6), which latter is secured to the wheel 21. The rear end 24 of the said pin extends through the wheel and into the slot 25 of the frame 2 (Fig. 5). By this arrangement, then, the angle through which the wheel 21 may be rotated is limited by the slot 25. Also secured upon the face of the wheel 21 are the pins 26 and 27. The pin 26 is adapted to be engaged by the dog 14 when the switch-hook is up, as shown by the dotted lines in Fig. 1. Now when the switch-hook 6 is pressed down the end 10 rises, and the dog 14 being in engagement with the pin 26, the wheel 21 is given a rotary motion in the direction indicated by the arrow. As the switch-hook approaches its uppermost posi-

tion the dog 14 comes into contact with the pin 15, and the pin 26 begins to slide off the dog 14, since the said pin is carried in a circular direction and the dog 14 in a vertical direction. By the time the switch-hook has reached its lowermost position, as shown by the full lines in Fig. 1, the dog 14 and the pin 26 are out of engagement, and the disk 21 being free returns to its normal position, after advancing as far as its momentum will take it, if it does not reach the limit of the slot 25. The force for thus restoring the said wheel is supplied by the release springs 28, 29 and 30, since the bushing 22, when the wheel was given its rotary motion, pressed the said springs into contact and out of normal position, thereby storing up force for restoring the disk 21 by straining or tensioning the springs 28, 29 and 30. Therefore, when the dog 14 and pin 26 disengage, the disk is immediately restored in the opposite direction. The pin 27 which, in the meantime, bears against the spring 19, as the disk completes its return motion, is caught by the angled section 31, thereby locking the said wheel in the position shown in full lines in Fig. 1. Were this spring 19 not provided the disk 21, when it completes its backward rotation, will again start a return motion and perhaps vibrate several times before being brought to rest. With this arrangement the disk is immediately brought to rest and locked upon the completion of the return motion. When the switch-hook is permitted to rise the spring 19 is carried out of engagement with the pin 27, and when the switch-hook is in its uppermost position the said spring takes the position shown by the dotted lines. The return motion of the wheel is limited by the pin end 24 coming into contact with the end of the slot 25. Suppose the switch-hook 6 is given a quick downward push, then the momentum gained by the wheel 21 may be sufficient (after the dog 14 and pin 26 disengage) to carry the said wheel a trifle farther. In this case the pin end 24 comes into contact with the other end of the slot 25, thus limiting the rotation of the wheel in this direction. Furthermore, when the switch-hook is down the arm 11 so operates the springs of the group D that the springs 32 and 33 disengage, springs 34 and 35 engage, and the springs 36 and 37 disengage. Of course, when the switch-hook is up the arm 11 passes out of engagement with the spring 35 and the disengaged springs engage, and the engaged springs disengage.

By referring to Fig. 8 it will be seen how my improved switch-hook device may be used in connection with an automatic substation, and in an automatic telephone system in connection with a connector switch of the type disclosed in United States Patent No. 815,176. When the receiver 38 is re-

moved from the switch-hook 6 the springs 36 and 37 engage, thereby placing the ground post 39 of the calling device A in connection with the substation ground G'. Also, the engagement of the springs 32 and 33 closes the local battery circuit through the transmitter 40, battery 41 and primary winding 42. The disengagement of the springs 34 and 35 removes the ringer 43 from across the line conductors 44 and 45. Then by operating the dial (not shown) which is carried on the shaft 51 of the keyboard A, the impulse wheel 52 is made to press the impulse springs 53 and 54 onto the ground post 39, delivering a suitable number of impulses first to the vertical line conductor 44 and then one to the rotary line conductor 45. As a result the vertical and rotary line relays 46 and 47 of the connector are energized, raising and operating the switch as is customary. After the vertical and rotary line relays 46 and 47 have been energized and the switch operated, the well known release of the connector may be brought about by restoring the receiver 38 to the switch-hook 6, which latter on its downward course rotates the disk 21, as previously explained; thus the springs 28, 29 and 30 are brought into contact, as a result grounding the vertical and rotary line conductors 44 and 45 simultaneously, which causes the vertical and rotary relays 46 and 47 to energize together, and as a result complete an energizing circuit through the release magnet 51^a. When the switch-hook is fully restored to its normal position the arm 11 bears against the spring 35 and closes the said spring in contact with spring 34, thereby bridging the ringer 43 across the line. Furthermore, the springs 32 and 33 are disengaged, which opens the local battery circuit through the transmitter 40. Also, the disengagement of the springs 36 and 37 removes the substation ground G' from the calling device A.

From the foregoing it will be seen that my switch-hook is adapted to operate the groups of springs E and D, which springs may be arranged or varied to control various circuits as desired. The same apparatus may, of course, be used to operate a selector like the one disclosed in United States Patent No. 815,321. In that case the line conductors 44 and 45 will terminate in the proper jacks of said switch. My invention may also be used where both selectors and connectors are used in making a call. It has been customary, heretofore, in automatic telephones to connect the switch-hook through the medium of a gear-wheel with a governor for regulating the speed of the downward stroke of the switch-hook; but in my telephone herein disclosed such an arrangement is absolutely unnecessary. The object in thus controlling the descending speed of the switch-hook has been to control the length

of time that the release springs 28, 29 and 30 are maintained in contact, as it has been found that if the length of contact has been too short the exchange apparatus will not have time to operate. In my telephone I provide a simple keyboard comprising the usual shaft 51 to which the dial is attached, as disclosed in United States Letters Patent No. 1,101,853, issued June 30, 1914, to Keith, Erickson and Erickson, for improvement in automatic telephone systems. Upon the said shaft there are mounted the usual gear-wheel 55, the impulse wheel 52 and a cam 56. This cam controls the secondary circuit springs so that when the dial is turned the said springs separate and the line conductors are kept apart while the impulses are being transmitted to the line. The gear-wheel 55 is geared to the governor 57, so that the return motion of the dial will be controlled. It will be seen, therefore, that I provide a very simple automatic telephone of the above type in which it makes no difference how quickly a subscriber moves down his switch-hook, so far as the releasing impulses are concerned. It will also be seen that I provide an improved, simplified and highly efficient hook-switch and calling mechanism for automatic telephone substations.

What I claim as my invention is:—

1. A subscriber's switch-hook, a rotary member operated by the upward movement of a portion of the switch-hook, a set of switch springs operated by said rotary member, and means including said switch springs whereby the said member is restored to normal position when the hook reaches the limit of its motion.
2. A subscriber's switch-hook, a rotary member operated by the upward movement of a portion of the switch-hook, a set of switch springs closed by the forward rotation of said member, and means including said switch springs whereby the said member is restored to normal position when the hook reaches the limit of its motion.

3. The combination of a switch-hook, a pivoted and spring-pressed catch on said hook, a rotary disk, a pin on the disk adapted to engage said catch when the hook is up, a set of switch springs, means on said disk for operating said switch springs, a second pin on the disk, a spring catch on the hook adapted to engage said second pin when the hook is down, and a pin on the hook for throwing said pivoted catch out of engagement with said first-mentioned pin when the hook reaches the limit of its downward movement.

4. In a telephone system, a switch-hook, springs, a rotary member provided with means for operating said springs, and means carried by the switch-hook for operating said rotary member by upward movement,

adapted to be disengaged therefrom when the switch-hook reaches the limit of its motion, one of said springs adapted to restore said member to normal position.

5. In a telephone system, a rotary member, a switch-hook provided with means for rotating said member by upward movement when the receiver is hung up, adapted to release the rotary member to permit the latter to rotate back to normal position when the switch-hook reaches the limit of its motion, and switch springs controlled by said rotary member.

6. In a telephone system, circuit-controlling springs, a wheel provided with a lateral projection for engaging and operating said springs, a pivoted switch-hook, a spring-pressed dog carried by said switch-hook, and means on said wheel to be engaged by said dog to cause the operation of said springs, said dog adapted to be disengaged from the wheel when the switch-hook reaches the limit of its downward motion, whereupon the wheel is then restored to normal position by one of said springs.

7. In a telephone system, a pivoted switch-hook, a wheel associated therewith, means carried by the switch-hook for operating the wheel, circuit-controlling springs operated by the forward rotation of the wheel, a locking spring carried by the switch-hook, and means on the wheel engaging said locking spring to hold the wheel in normal position.

8. In a telephone system, a pivoted switch-hook, a dog pivoted on said hook, means for limiting the motion of the dog in one direction relative to the hook, a spring normally holding the dog at the limit of its motion in said one direction, a wheel associated with the hook, means on the wheel to be engaged by said dog when the hook rises, adapted to cause the rotation of the wheel when the hook descends, and circuit-controlling springs operated by the forward rotation of said wheel, the upward motion of said dog being sufficient to automatically disengage it from the wheel when the hook reaches the limit of its downward motion, whereupon the wheel is then restored to normal position by one of said circuit-controlling springs.

9. In a telephone system, a pivoted switch-hook, a wheel associated therewith, a spring on the hook, a projection on the side of the wheel adapted to engage said spring to lock the wheel in normal position, said spring having a straight portion upon which the said projection rides while the wheel is returning to normal position, means carried by the switch-hook for operating said wheel by the downward motion of the hook, and circuit-controlling springs operatively controlled by the forward rotation of the wheel when the receiver is hung up.

10. In a telephone system, a bracket plate, a switch-hook pivoted between its ends thereon, a set of circuit-controlling springs controlled by said switch-hook, adapted to be 45
 5 disengaged when the switch-hook rises, a wheel mounted on the bracket plate, another set of circuit controlling springs, means on said wheel for operating said second set of springs, and means on an upwardly-mov-
 10 able part of the switch-hook for rotating the wheel when the receiver is hung up.
11. In a telephone system, a hook-switch mechanism comprising a wheel adapted to be rotated by the upward motion of a part 15
 15 of the switch-hook, means for rotating said wheel back to normal, means whereby said wheel is automatically released by the switch-hook to rotate back to normal position when the hook reaches the limit of said
 20 motion, and switch springs controlled by said wheel.
12. In a telephone system, a wheel, a switch-hook, means by which the hook rotates the wheel in one direction by upward 25
 25 movement when the receiver is hung up, and spring means for rotating the same in the other direction independent of the switch-
 hook.
13. A subscriber's switch hook, a rotary member operated by the upward movement of a section of the hook, a set of switch 30
 30 springs operated by said rotary member, and automatic mechanical means including said switch springs whereby the said member
 35 is restored to normal position when the hook reaches the limit of its motion.
14. A subscriber's switch hook, a rotary member operated by an upward movement of a section of the switch hook, a set of 35
 40 switch springs closed by the forward rotation of said member, and automatic mechan-
 ical means including said switch springs whereby the said member is restored to normal position when the hook reaches the limit 45
 of its motion.
15. In a telephone system, a switch hook, springs, a rotary member for operating said springs, and controlled by said switch hook upon the upward movement of the same, a mechanical arrangement for disengaging 50
 the rotary member from the switch hook when the latter reaches the limit of its motion, said rotary member being under the control of one of said springs whereby the rotary member is restored to normal posi- 55
 tion.
16. In a telephone system, a pivoted switch hook, a wheel associated therewith and operated by the switch hook, circuit controlling springs under the control of the wheel 60
 upon its forward rotation, a locking spring carried by the switch hook, a catch on the wheel engaging the locking spring to hold the wheel in normal position.
17. In a telephone system, a bracket plate, 65
 a switch hook pivoted between its ends thereon, a set of circuit controlling springs controlled by said switch hook adapted to be engaged when the switch hook rises, a wheel mounted on the bracket plate, another set 70
 of circuit controlling springs, a projection on said wheel for operating said second set of springs, and a controlling arm on the switch hook arranged to rotate the wheel by an upward movement when the receiver 75
 is hung up on the hook.

Signed by me at Chicago, Cook county, Illinois, this 8th day of November, 1906.

JOHN ERICKSON.
